UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM.

1,345,508.

Specification of Letters Patent.

Patented July 6, 1920.

Application filed August 15, 1919. Serial No. 317,821.

To all whom it may concern:

Be it known that I, EPPA H. RYON, a citizen of the United States, residing at Waltham, in the county of Middlesex and State 5 of Massachusetts, have invented a new and useful Weft-Detecting Mechanism, of which the following is a specification.

This invention relates to a weft-detecting mechanism for automatic looms, more particularly designed for looms of this class in 10 which provision is made for replenishing the weft carrier before the weft thereon is entirely exhausted.

It is a general object of my invention to 15 provide means associated with the transferrer for giving the detector a detecting movement during the downward movement of the transferrer. Preferably the detector is mounted on the transferrer and is moved 20 to detecting position on each alternate beat of the lay.

Another object of my invention is to provide a pneumatic device for actuating the detector, preferably adjustable as to the relative time of operation. In the form of my 25 invention shown in the drawing, the pneumatic device is mounted on the transferrer and becomes operative by engagement with an adjustably fixed stop, thereby giving the 30 detector a detecting movement at any desired point in the movement of the trans- ferrer.

My invention further relates to arrangements and combinations of parts hereinafter 35 described and more particularly pointed out in the appended claims. A preferred form of my invention is shown in the drawings, in which—

Figure 1 is a front view of my improved 40 detecting mechanism;

Fig. 2 is a partial left-hand side elevation of the transferrer;

Fig. 3 is a plan view of a portion of the 45 transferrer and the detecting mechanism mounted thereon;

Fig. 4 is a sectional front elevation taken along the line 4—4 in Fig. 2;

Fig. 5 is a left-hand side elevation similar 50 to Fig. 2, but showing also the resetting mechanism;

Fig. 6 is a detail sectional elevation taken along the line 6—6 in Fig. 3;

Fig. 7 is a detail front elevation of the re- 55 setting lever, and

Fig. 8 is a detail sectional view taken 55 along the line 8—8 in Fig. 5.

Referring to the drawings, I have shown a portion of a stationary weft carrier magazine frame 10, having a short shaft or stud 11 secured therein upon which a transferrer 60 12 is pivoted. A rod 13 (Fig. 4) is mounted to slide horizontally in the outer end of the transferrer arm, being normally moved to the right as shown in Fig. 4.

When the weft detector operates to indicate weft exhaustion, the rod 13 is moved to the left, as indicated in dotted lines in the lower part of Fig. 1. When the transferrer thereafter moves upward with the rod 13 in its left-hand position, the rod engages a 70 cam 14 on an arm 15 (Figs. 7 and 8) and moves the arm rearward. The arm is mounted on a fixed pivot at 16 and supports a segment gear 17 which moves downward as the arm 15 moves to the rear. Such 75 movement of the gear 17 is operable through connections not shown to release a weft carrier for advance to the transfer point.

The transferrer 12 is preferably given a downward or transferring movement on 80 each alternate beat of the lay by a rod 18 actuated by connections not shown from any convenient moving part of the loom.

The parts thus far described are substantially the same as those shown in my prior 85 application #273,671, filed January 28, 1919, to which application and also to my prior application #244,637, filed July 12, 1918, reference is made for a more complete description of the operation of the 90 parts.

The detector 20 in my present invention is pivoted at 21 to a lever 22, which in turn is pivoted at 23 to the laterally projecting head 24 of the transferrer 12. A light coil 95 spring 25 normally holds the lever 22 and detector 20 in the raised position shown in full lines in Fig. 1. An adjustable stop 26 on the lever 22 limits the movement of the detector in one direction.

An actuating lever 27 (Fig. 4) is pivoted at 28 to the transferrer head 24. The right end of the lever 27 rests upon the lever 22 upon which the detector is mounted, the lever also engaging the flat upward extension 29 of the detector 20 and pressing the extension 29 against the stop 26. The left-hand arm 30 of the lever 27 carries an

adjustable stud 31 which rests upon a plunger 32 slidably mounted in a cylindrical recess 33 in the head 24. The recess 33 is connected by a passage 34 with a cylindrical recess 35 formed in an arm 36 projecting upwardly from the transferrer 12. A plunger 37 is slidably mounted in the recess 35 and is normally pressed outward by a coil spring 38. A stop 39 is adjustably secured 10 in the magazine frame 10 in position for engagement by the plunger 37 as the transferrer moves downward.

Having described the details of construction of my improved detecting mechanism, 15 I will now describe the operation thereof.

The normal position of the parts is shown in full lines in Figs. 1 and 4. As the transferrer is moved downward by the rod 18 on each alternate beat of the lay, the plunger 20 37 engages the stop 39 and is forced thereby into the cylinder 35, compressing the spring 38 and also the air contained in the cylinder. The plunger 32 in the recess 33 is normally held in its lower or inner position by pressure transmitted from the spring 25. When 25 the plunger 37 is forced into the cylinder 35, however, a portion of the air compressed in the cylinder 35 is forced into the passage 34, raises the piston 32, and moves the lever 30 22 to the position shown in dotted lines in Fig. 1.

If a sufficient supply of weft remains on the weft carrier, the teeth of the detector 20 engage the weft, holding the detector in 35 the position shown in dotted lines in Fig. 4, in which position the detector can not move the rod 13. If, however, the weft on the weft carrier is substantially exhausted, the lower end of the detector slides along the 40 weft carrier to the position indicated in dotted lines in Fig. 1, the upper extension 29 of the detector acting as a cam to move the rod 13 to the left, as also indicated in the lower position of Fig. 1.

45 The subsequent operation of the rod 13 against the arm 15 has been previously described. As the transferrer thereafter completes its upward stroke, the rod 13 engages an inclined portion 40 (Fig. 7) on the arm 50 15 and is returned thereby to normal position.

Several advantages are obtained through 55 the use of pneumatically controlled operating mechanism. By the adjustment of the stop 39, the operation of the detector 20 may be timed for any desired point in the stroke of the transferrer and by the provision of a plunger 37 of sufficient size, almost instantaneous operation of the detector may be secured.

The detector 20, lever 22 and actuating lever 27, should preferably be as light as possible and are commonly made of aluminum.

60 Having thus described my invention, it

will be evident that changes and modifications can be made therein by those skilled in the art within the scope of my invention as set forth in the claims, and I do not wish to be otherwise limited to the details herein 70 disclosed, but what I claim is:—

1. In a loom, a transferrer, means to give 75 said transferrer a transferring movement at every alternate beat of the lay; a detector mounted on said transferrer, a member effective to give said detector a detecting movement, and an actuating device for said member mounted on said transferrer, said device being rendered operative by co-operation with an additional element as the 80 transferrer moves downward.

2. In a loom, a weft detector, a transferrer, and a pneumatic device actuated by 85 said transferrer to give said detector a detecting movement.

3. In a loom, a transferrer, a weft detector, and a pneumatic device rendered effective to give said detector a detecting movement by downward movement of said 90 transferrer.

4. In a loom, a transferrer, a weft detector, and a pneumatic device mounted on and movable with said transferrer and rendered effective to give said detector a detecting movement by downward movement 95 of said transferrer.

5. In a loom, a transferrer, a lever pivoted thereon, a detector supported by said lever, a member effective to move said lever and detector to operative position, and an actuating device for said member mounted on 100 said transferrer, said device being rendered operative by co-operation with an additional element as the transferrer moves downward.

6. In a loom, a transferrer, a weft detector mounted thereon, a pneumatic device, and connections between said device and 105 said detector whereby said device is effective to give said detector a detecting movement as the transferrer moves downward.

7. In a loom, a transferrer, a weft detector mounted thereon, a pneumatic device mounted on said transferrer, and connections between said device and said detector whereby said device is effective to give said detector a detecting movement as the transferrer moves downward.

8. In a loom, a transferrer, a lever pivoted thereon, a detector supported by said lever, an actuator for said lever, and a pneumatic device mounted on said transferrer, rendered effective to move said actuator by downward movement with said transferrer.

9. In a loom, a transferrer, a lever pivoted thereon, a detector supported by said lever, an actuator for said lever, and a pneumatic device to move said actuator as said transferrer moves downward.

10. In a loom, a transferrer, a lever 130

piyoted thereon, a detector supported by said lever, an actuator for said lever, pivoted on said transferrer, a plunger engaging said actuator, and a pneumatic device to move 5 said plunger as said transferrer moves downward.

11. In a loom, a transferrer, means to give said transferrer a transferring movement, a detector mounted thereon, an air-compressing device on said transferrer, a 10 fixed stop engaged thereby on each downward stroke of the transferrer whereby said air-compressing device is actuated, and connections between said device and said detector through which said detector is given 15 a detecting movement.

12. In a loom, a transferrer, means to give said transferrer a transferring movement, a detector mounted thereon, said transferrer having two separate cylindrical recesses therein, and having also a passage connecting said recesses, a spring pressed plunger in one recess positioned to engage a fixed stop as the transferrer moves downward, 20 said plunger being depressed thereby, and a plunger in the second recess connected to actuate the detector when the first plunger is depressed.

In testimony whereof I have hereunto affixed my signature.

EPPA H. RYON.
